DOLL EYE MECHANISM

William Lorenz and Lazurus W. Pollack, New York, N. Y.; said Pollack assignor to said Lorenz

Application July 10, 1933, Serial No. 679,604

16 Claims. (Cl. 46—40)

This invention relates to new and useful improvements in an eye mechanism for dolls and the like.

The invention has for an object the construction of an eye mechanism which is characterized by a pair of hemispherical eyes developed from sheet stock and also having opposed bridge pieces of the same stock adapted to be slidably associated with each other.

Still further the invention proposes the arrangement of means upon the outer sides of the hemispherical eyes adapted to engage the inner sides of the head of a doll to pivotally support the eyes.

Still further it is proposed to arrange the means mentioned in the previous paragraph as comprising cylindrical bearings developed from the stock of the hemispherical eyes.

Furthermore as another object of this invention it is proposed to associate a gravity member with the bridge pieces so that the lugs from one of the bridge pieces engage the gravity member for forming the connection and the other bridge piece is slidably held by the same lugs.

Still further an arrangement is proposed for associating a weight with the gravity member in a manner so that when the hemispherical eyes are extended as allowed by the bridge pieces when the device is mounted in a doll's head, that the weight be substantially balanced relative to the hemispherical eyes.

Still further the invention contemplates a modified arrangement for mounting the hemispherical eyes within a doll's head and more particularly comprising a wire frame adapted to have its ends engaged into the sides of the doll's head and associated with the hemispherical eyes to pivotally support the latter mentioned hemispherical eyes mentioned in the previous paragraph with semicircular cutouts at the sides adapted to partially encircle portions of the wire of said supporting means.

Still further an arrangement is proposed whereby the supporting wire is formed with offset portions arranged so that the hemispherical eyes may be moved together as allowed by the bridge pieces to positions in which the semicircular openings disengage from the support wire to allow removal of the eye mechanism.

Furthermore as another object of this invention it is proposed to associate a resilient member with the eye mechanism in a manner so that the eye mechanism resiliently maintains its position and may be removed when desired.

Furthermore as another object it is proposed to arrange the resilient member mentioned in the previous paragraph comprising a flat spring adapted to be detachably mounted upon the eye mechanism and engaging against the holding frame.

Still further the invention proposes the cutouts at the sides of the hemispherical eyes in a manner so that the eye mechanism may be directly removed against the action of the resilient member mentioned in the previous two paragraphs.

Furthermore as another object of this invention a novel arrangement is proposed for constructing the ends of the supporting wire in a manner so that the wire may readily be mounted in place within the doll's head.

Still further the invention proposes the construction of a device as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a transverse vertical sectional view of a doll's head eye mechanism according to this invention.

Fig. 2 is a horizontal sectional view taken on the line 2—2 of Fig. 3.

Fig. 3 is a perspective view of the eye mechanism illustrated in Figs. 1 and 2, but shown per se.

Fig. 4 is a developed view of the hemispherical eyes and associated stock.

Fig. 5 is a perspective view similar to Fig. 3 but showing a modified arrangement.

Fig. 6 is a view similar to Fig. 2 but showing the eye mechanism illustrated in Fig. 5 in position.

Fig. 7 is another view similar to Fig. 2 but illustrating a still further modified arrangement.

Fig. 8 is a perspective view of a resilient member used in the form of the invention shown in Fig. 7.

Fig. 9 is a fragmentary vertical sectional view taken on the line 9—9 of Fig. 7.

Fig. 10 is a perspective view of the eye mechanism of Fig. 7.

Referring to Figs. 1—4 inclusive the eye mechanism comprises a pair of similar hemispherical

eyes 10 and 11 each developed from sheet material having bridge pieces 12 and 13 respectively. The stock from which the hemispherical eyes are formed also includes side portions 14 for developing cylindrical bearings hereinafter more fully described. The outer surface of the hemispherical eyes 10 and 11 are pointed or in any other manner formed with representations of the eyes and lids. The bridge pieces 12 and 13 are of slightly different widths with the wider one, namely bridge piece 13 formed with lugs 15 projecting from the top and bottom edges. The bridge pieces 12 and 13 conversely are slightly concaved as clearly illustrated in Fig. 1 so as to add rigidity. These bridge pieces are placed one against the other in face contact with each other and are slidingly associated by reason of the lugs 15 engaging over the edges of the bridge piece 12.

20 The eye mechanism is also provided with a gravity member attached upon the bridge pieces in a novel manner so as not to interfere with relative sliding of the bridge pieces. More particularly the lugs 15 extend through openings 16 formed in the gravity member 17. The lugs then have their free ends turned so as to maintain their positions. The bridge piece 12 is engaged between the bridge piece 13 and the gravity member 17. The gravity member comprises merely a 30 vertical strip supporting a weight 18 at its lower end and provided at the top and bottom ends with cushion elements 19. These cushion elements are in the form of small rubber blocks engaged into cutouts at the ends of the gravity member.

35 These cushion members 19 are adapted to strike against the inside of a doll's head 20 so as to to cushion the effect of the swinging gravity member as hereinafter more fully described. The cushion members furthermore prevent noises produced if the ends of the gravity member would be allowed to strike the inside of the doll's head.

40 The doll's head 20 is formed with conventional eye openings 21 through which the hemispherical eyes extend. The portions 14 are turned in cylindrical bearings 14' which bearings are adapted to engage into openings 22 formed at the sides in the doll's head for the purpose of supporting the eyes in a manner so that they may swing to positions in which the lids cover the openings 21 or in which the eyes are fully exposed. According to this invention the hemispherical eyes may be moved toward each other since the bridge pieces 12 and 13 are slidably arranged for the purpose of disengaging the cylindrical bearings 45 14' on the openings 22 to remove the eyes. The tolerances of the eye openings 21 and the hemispherical eyes must be sufficient to allow the removal of the eyes as mentioned. Similarly the engagement of the eyes within the doll's head is very simple since it is merely necessary to extend the hemispherical eyes until the cylindrical bearings 14' assume positions within the openings 22. The weight 18 is offset to one side relative to the gravity member 17 so as to be in true balance when the hemispherical eyes 10 and 11 are extended from each other when mounted within the doll's head. It should be noticed that the strip 17 is in fixed relation with the bridge piece 13 and therefore the weight 18 should be extended to the side of the movable hemispherical eye 10.

50 In Figs. 5 and 6 a variation of the invention has been disclosed which distinguishes from the previous form merely in the manner in which the eye mechanism is mounted within the doll's head. The construction of the hemispherical eyes, their association with each other, and the gravity member is identical to the form previously described and the same parts may be recognized by the same reference numerals. The 5 construction differs from the previous form in the provision of semicircular cutouts 23 formed with the sides of the hemispherical eyes 10 and 11 in lieu of the cylindrical bearings 14'. The eye mechanism is mounted within the doll's head by reason of a wire frame comprising a central handle portion 24 and oppositely directed ends 25 engaging into the openings 22 in the sides of the interior of the doll's head. The ends 25 are adapted to pass through the openings 15 23 as clearly illustrated in Fig. 6 to hold the eye mechanism in place. The wire frame is provided with offset portions 26 immediately adjacent the ends 22 arranged so that the hemispherical eyes 10 and 11 may be moved towards 20 each other as allowed by the bridge pieces 12 and 13 to positions in which the outer ends of the openings 23 disengage from the ends 25 so that the eye mechanism may be removed. The eye mechanism may be inserted in place 25 conversely to the manner in which it is removed. There must be sufficient tolerances between the eyes and their sockets to allow their removal and replacement. The wire frame preferably should be made from pliable material so that it may 30 be engaged within the doll's head by merely forcing the ends 25 apart into position within the openings 22.

35 The eye mechanism may also be placed in position without disturbing the set distance between the hemispherical eyes 10 and 11 by forcing the said mechanism behind the offset portions 26. The upper portion 17' of the strip 17 is made of resilient material and permits a deflection from its normal position when its 40 upper extremity 17a is forced against the inner surface of the doll head 20. The mechanism may be forced up behind offset portions 26 from the open bottom of the head, with suitable tools, first the portion 17' is deflected under the pressure until the concave portions of bridge pieces 12 and 13 are in alignment with the offset portions 26 where the bridge pieces snap into engaging position. In this location the doll eye mechanism is held in functioning position and 50 strip portion 17' assumes its natural normal direction. The normal direction of the elastic strip portion 17' prevents accidental disengagement of the bridge pieces from the offset portions 26 and the doll eye mechanism may be 55 removed from head 20 only by forcing the strip portion to a deflected position and simultaneously pulling downward on the said mechanism.

60 In Figs. 7-10 inclusive another form of the invention has been disclosed which is very similar to the form illustrated in Figs. 5 and 6 except for the provision of another resilient arrangement to hold the eye mechanism in place. This resilient arrangement comprises a resilient member formed of a flat spring having a central 65 portion 28 with sloping sides so as to be capable of being jammed in beneath the inturned lugs 15 so as to maintain its position. This spring is formed with enlarged ends 29 adapted to engage against the offset sides 26 of the holding 70 wire frame.

70 The outer ends of the hemispherical eyes 10 and 11 are formed with openings 23' substantially semicircular in shape except for the fact that one of the sides is cut away to form an inclina- 75

tion so that the eye mechanism may be moved downwards (or upwards if so designed) to disengage the eye mechanism from the supporting frame as previously described. The spring 28, 5 29 must be moved transversely to disengage from the lugs 15. When in place the spring 28, 29 presses against the offset portions 26 as clearly illustrated in Fig. 7 and so maintains the eye mechanism with the hemispherical eyes extended 10 through the openings 21.

This above arrangement also contains the feature of the mounting present in the form of the invention illustrated in Figs. 5 and 6, that is the hemispherical eyes 10 and 11 may be moved 15 toward each other as permitted by the bridge pieces 12 and 13 to positions in which the openings 23' disengage from the ends of the supporting wire frame. The ends 25' of the wire frame distinguish slightly from the previous ends in 20 that they are formed by slitting the ends and bending one of the halves indicated by reference numeral 30 at right angles to act as stops against the material of the doll's head. The other split end 31 may be sharpened and constitutes the portion which engages into the doll's 25 head. The split end 30 terminates in another bent portion 32 which also anchors in the doll head 20 to prevent any rotary action of the wire frame. In this arrangement it is not necessary 30 that openings be provided in the doll's head since the pointed ends 31 may be forced into the material of the head.

While we have shown and described the preferred embodiment of our invention, it is to be understood that we do not limit ourselves to the precise construction herein disclosed and the right is reserved to all changes and modifications coming within the scope of the invention as defined in the appended claims.

Having thus described our invention, what we claim as new, and desire to secure by United States Letters Patent is:—

1. In an eye mechanism for dolls and the like, a pair of hemispherical eyes having opposed bridge pieces slidably associated with each other, a gravity member attached upon one of said bridge pieces, said gravity member including a vertical strip, and lugs from said bridge piece engaging through said strip to hold the strip in place and engaging over the edges of the other bridge piece to simultaneously slidably connect the bridge pieces.

2. An eye mechanism for dolls and the like, comprising a pair of hemispherical eyes developed from sheet material and each having opposed bridge pieces of the same stock slidably associated with each other, a gravity member attached upon one of said bridge pieces, and means for horizontally pivotally mounting said eyes in a doll's head, said bridge pieces being in face contact with each other, said gravity member including a vertical strip in contact with the free side of one of said bridge pieces, and lugs on the other of said bridge pieces engageable with the edges of said bridge piece and engaging through openings in said strip for mounting the eyes upon the gravity member and simultaneously holding the bridge pieces in slidable association with each other.

3. An eye mechanism for dolls and the like, comprising a pair of hemispherical eyes developed from sheet material and each having opposed bridge pieces of the same stock slidably associated with each other, a gravity member attached upon one of said bridge pieces, and means

for horizontally pivotally mounting said eyes in a doll's head, comprising cylindrical bearings developed upon the outer ends of said hemispherical eyes from the same stock and adapted to engage in openings in the inside of the doll's head. 5

4. In an eye mechanism for dolls and the like, a pair of hemispherical eyes and each having opposed bridge pieces slidably associated with each other, and means for horizontally pivotally mounting said eyes in a doll's head, comprising elements projecting from the outer ends of the hemispherical eyes and adapted to engage in openings in the doll's head as the bridge pieces are moved apart. 10

5. In an eye mechanism for dolls, a pair of 15 hemispherical eyes developed from sheet stock and each having opposed bridge pieces of the same stock slidably associated with each other and each also having cylindrical bearings developed on the outer ends of said hemispherical 20 eyes from the same stock for engaging openings in the doll's head to pivotally mount the eyes.

6. An eye mechanism for dolls and the like, comprising a pair of hemispherical eyes developed from sheet material and each having opposed bridge pieces of the same stock slidably associated with each other, a gravity member attached upon one of said bridge pieces, and means for horizontally pivotally mounting said eyes in a doll's head, comprising a wire frame having 25 30 opposed ends engaged upon the opposite inner sides of the doll's head, and said hemispherical eyes being formed with semicircular openings engaged over said ends.

7. An eye mechanism for dolls and the like, comprising a pair of hemispherical eyes developed from sheet material and each having opposed bridge pieces of the same stock slidably associated with each other, a gravity member attached upon one of said bridge pieces, and means for horizontally pivotally mounting said eyes in a doll's head, comprising a wire frame having opposed ends engaged upon the opposite inner sides of the doll's head, and said hemispherical eyes being formed with semicircular openings engaged 45 50 over said ends, said wire frame having offset portions adapting the hemispherical eyes to be moved together in a manner so that the semicircular openings disengage therefrom allowing removal of the eye mechanism.

8. An eye mechanism for dolls and the like, comprising a pair of hemispherical eyes developed from sheet material and each having opposed bridge pieces of the same stock slidably associated with each other, a gravity member attached 55 upon one of said bridge pieces, and means for horizontally pivotally mounting said eyes in a doll's head, comprising a wire frame having opposed ends engaged upon the opposite inner sides of the doll's head, and said hemispherical eyes 60 being formed with semicircular openings engaged over said ends, said wire frame including a handle at the center arranged in one continuation so that the ends of the wire frame may be moved apart to disengage the openings in the doll's 65 head.

9. An eye mechanism for dolls and the like, comprising a pair of hemispherical eyes developed from sheet material and each having opposed bridge pieces of the same stock slidably associated with each other, a gravity member attached upon one of said bridge pieces, means for horizontally pivotally mounting said eyes in a doll's head adapted to release the eyes upon sliding of the eyes in a specific direction, and means for resil- 70 75

- iently holding said eye mechanism from sliding in said direction.
10. An eye mechanism for dolls and the like, comprising a pair of hemispherical eyes developed from sheet material and each having opposed bridge pieces of the same stock slidably associated with each other, a gravity member attached upon one of said bridge pieces, means for horizontally pivotally mounting said eyes in a doll's head, and comprising a wire frame having outward directed ends engaged in opposite sides of the inside of the doll's head, said hemispherical eyes having openings at the sides engaging said ends and adapted to be moved in one direction to disengage therefrom, and a resilient member mounted upon said eye mechanism adapted to engage against the wire frame for resiliently holding the eye mechanism in place.
11. An eye mechanism for dolls and the like, comprising a pair of hemispherical eyes developed from sheet material and each having opposed bridge pieces of the same stock slidably associated with each other, lugs on one of said bridge pieces, a gravity member attached upon one of said bridge pieces, means for horizontally pivotally mounting said eyes in a doll's head, and comprising a wire frame having outward directed ends engaged in opposite sides of the inside of the doll's head, said hemispherical eyes having openings at the sides engaging said ends and adapted to be moved in one direction to disengage therefrom, and a resilient member mounted upon said eye mechanism adapted to engage against the wire frame for resiliently holding the eye mechanism in place, said resilient member comprising a flat spring having a central portion with inclined sides adapted to be clamped by sliding upon said lugs.
12. An eye mechanism for dolls and the like, comprising a pair of hemispherical eyes developed from sheet material and each having opposed bridge pieces of the same stock slidably associated with each other, a gravity member attached upon one of said bridge pieces, and means for horizontally pivotally mounting said eyes in a doll's head adapted to release the eyes upon sliding of the eyes in a specific direction, said gravity member including a vertical strip, lugs projecting from the edges of one of said bridge pieces engaging over the edges of the other and through openings in said vertical strip for mounting the bridge pieces upon the strip and slidably holding the bridge pieces relative to each other, a spring wedged in between said lugs, and said means for horizontally pivotally mounting said eyes including a wire frame having opposed ends mounted upon the opposite inner sides of the doll's head, said spring acting against said frame for resiliently holding the eye mechanism in place by holding the eyes from sliding in said direction.
13. In an eye mechanism for dolls and the like, a pair of hemispherical eyes and each having opposed bridge pieces slidably associated with each other, a gravity member attached upon one of said bridge pieces, means for horizontally pivotally mounting said eyes in a doll's head, said gravity member including a vertical strip with a weight mounted thereon, and said weight being offset from the center of the distance between said eyes in a normal position of said bridge pieces to compensate for the sliding association of the hemispherical eyes when engaged in a doll's head so that the weight then is at the center.
14. In an eye mechanism for dolls and the like, a wire frame for supporting the eye mechanism within the doll and including oppositely directed ends, a pair of hemispherical eye members, said hemispherical eyes being formed with substantially semicircular side openings to accommodate the said wire frame when the doll eye mechanism is in operating position, a concaved bridge piece connecting said eye members, a perpendicular strip secured to the said bridge piece, a gravity member attached upon one side of the said perpendicular member, the other side of the perpendicular member being sufficiently resilient to permit sliding the eye mechanism into functioning position in engagement with the said wire frame.
15. In an eye mechanism for dolls and the like, a pair of hemi-spherical eyes and each having opposed bridge pieces slidably associated with each other, a gravity member attached upon one of said bridge pieces, said gravity member including a vertical strip transverse of said bridge pieces, and lugs from said bridge piece engaging through said strip to hold the strip in place and engaging over the edges of the other bridge piece and simultaneously slidably connecting said bridge pieces.
16. An eye mechanism for dolls and the like, comprising a pair of hemi-spherical eyes developed from sheet material and each having opposed bridge pieces of the same stock slidably associated with each other, a gravity member attached upon one of said bridge pieces, and means for horizontally pivotally mounting said eyes in a doll's head, said bridge pieces being in face contact with each other, said gravity member including a vertical strip in contact with the free side of one of said bridge pieces, and lugs on the other of said bridge pieces engageable with the edges of said bridge piece and engaging through openings in said strip for mounting the eyes upon the gravity member and simultaneously holding the bridge pieces in slidable association with each other, said lugs being arranged upon the edge of the bridge piece.

WILLIAM LORENZ.

LAZURUS W. POLLACK.
